UNITED STATES PATENT OFFICE.

HENRY ALBERT FLEUSS, OF THATCHAM, ENGLAND, ASSIGNOR TO THE PULSOMETER ENGINEERING COMPANY, LIMITED, OF READING, ENGLAND.

AIR-PUMP.

1,050,767.

Specification of Letters Patent.

Patented Jan. 14, 1913.

Application filed June 24, 1912. Serial No. 705,493.

To all whom it may concern:

Be it known that I, HENRY ALBERT FLEUSS, a subject of the King of Great Britain, residing at Dunstan Lodge, Thatcham, 5 Berkshire, England, have invented new and useful Improvements in Air-Pumps, of which the following is a specification.

This invention relates to air pumps in which the air delivery valve is at the top 10 of a vertical pump cylinder and opens upward into a receiving chamber the lower part of which is filled with liquid as for example with oil. In pumps of this class the delivery valve is usually lifted by the piston 15 as it is brought to the top of its upward stroke and air and oil previously contained in the cylinder is then delivered past the valve into the receiving chamber while on the first portion of the down stroke of the 20 piston some oil is allowed to pass back into the cylinder above the piston by the valve remaining held open by the piston during the first portion of its downward stroke.

Such pumps as heretofore constructed if 25 worked at too high a speed lose their efficiency owing to the fact that sufficient time is then not allowed for the air to separate from the oil before it passes back into the cylinder on the downward stroke of the 30 piston and the vacuum that can be obtained by the downward stroke of the piston is thereby impaired. To remedy this I make the lower end of the receiving chamber to open into a bath of liquid surrounding its 35 exterior and also make openings through the upper end of the receiving chamber through which liquid rising upward through the chamber can overflow and pass downward to reenter the chamber at its lower end.

40 The air and oil injected upward past the delivery valve create an upward current through the interior of the chamber and a downward return current on its exterior so that the liquid passing back into the chamber 45 through the openings in its lower end is always liquid from which air has had time to separate and when the piston descends in the pump cylinder the liquid drawn into the pump cylinder is practically 50 free from air.

In order to insure that the air and oil ejected past the delivery valve shall be directed upward into the interior of the receiving chamber and not allowed to spread laterally, I preferably make the underside 55

of the pump cylinder cover to cone upward to a valve seat at its center as heretofore and as heretofore I make the valve in the form of an inverted cone which near its upper end fits into the valve seat which is 60 correspondingly coned and of small depth so that the lower part of the coned valve extends downward for some distance below the valve seat. The slope of the coned sides of the valve I make such that the sides if 65 prolonged would meet the solid inner sides of the receiving chamber thus when the valve is lifted and oil and air rush upward past its sloping sides they come against the inner sides of the receiving chamber and are 70 deflected upward and not allowed to spread laterally.

Figures 1 and 2 show vertical sections of 75 two examples of air pumps constructed according to my invention.

In Fig. 1 *a* is the pump barrel or cylinder, *b* the delivery valve at its upper end, *c* the inlet for air to pass to the interior of the pump barrel from a chamber *d* from which a pipe *e* extends to the vessel to be exhausted. *f* is the receiving chamber above the top of the pump barrel, *g* are openings through the lower end of the sides of this chamber and *h* are openings through their upper end, *i* is an outer chamber containing 80 oil by which the receiving chamber *f* is surrounded. *k* is the piston and *l* the piston rod extending as usual through the center of the delivery valve *b* and through the cover of the receiving chamber *f*. *m* is a coiled 85 spring by which the delivery valve is pressed downward.

In Fig. 2 the parts corresponding to those shown in Fig. 1 are marked with similar letters of reference. In this example the receiving chamber *f* in place of being secured to the cover of the pump barrel as shown in Fig. 1 is held up to the cover of the outer chamber *i*. The outlet from the upper end of this chamber is adapted to have a pipe led 95 away from it to the suction inlet of a second pump.

What I claim is:—

1. In an air pump the combination of a pump barrel, a delivery valve at its upper 105 end, a receiving chamber above the top of the pump barrel, a bath of oil or like liquid outside the receiving chamber and openings both at top and bottom of the receiving chamber by which liquid can pass to and 110

from the bath of liquid and the interior of the receiving chamber.

2. The combination of a pump barrel, a cover closing the top of this barrel coned upward on its underside to a valve seat at its center, a valve resting at its upper end in this seat and coned downward and extending for some distance below the seat, a receiving chamber above the top of the pump barrel, an outer casing containing oil

or like liquid surrounding the receiving chamber and openings both at top and bottom of the receiving chamber by which liquid can pass to and from the bath of liquid and the interior of the receiving chamber.

HENRY ALBERT FLEUSS.
